UNITED STATES PATENT OFFICE.

PAUL H. ZIMMER, OF SCHENECTADY, NEW YORK, ASSIGNOR TO GENERAL ELECTRIC COMPANY, A CORPORATION OF NEW YORK.

CONTROLLER FOR ELECTRIC MOTORS.

1,343,021.

Specification of Letters Patent. Patented June 8, 1920.

Application filed January 8, 1919. Serial No. 270,170.

To all whom it may concern:

Be it known that I, PAUL H. ZIMMER, a citizen of the United States, residing at Schenectady, in the county of Schenectady,

5 State of New York, have invented certain new and useful Improvements in Controllers for Electric Motors, of which the following is a specification.

My invention relates to starting devices 10 for electric motors and has for its object the provision of improved means whereby an electric motor may be started and brought up to running speed in a reliable, simple and efficient manner.

15 My invention relates more specifically to starting devices in which a switch is first closed to make a starting connection and subsequently a second or running switch is closed and the first switch opened.

20 My invention is particularly applicable to the starting of alternating current motors of the type which are connected to a source of low voltage for starting and then connected directly to the line voltage for running.

25 One method of accomplishing this result automatically is to provide two switches, one of which is first closed under manual control to make the starting connection and then at the proper time a second 30 switch which makes the running connection is automatically closed and the first switch opened. I have disclosed my invention in connection with an arrangement of this general character although certain features 35 thereof may have a more general application.

In carrying out my invention in one form I provide two electromagnetically actuated switches, one for making the starting connection which I have illustrated as a connection to a compensator or auto-transformer for applying a reduced voltage to the motor while the other switch in closing connects the motor direct to the line. The 45 two switches are so interlocked that they

cannot both be closed at the same time and the connections are such that the closing of the first switch sets in operation a timing device which after the lapse of a predetermined interval energizes the second switch and deenergizes the first switch.

In the accompanying drawings illustrating one embodiment of my invention, Figure 1 is a front elevation of a switch embodying 55 my improvements; Fig. 2 is a side view of

the same; Fig. 3 is a detailed view of the switch mechanism; Fig. 4 is a sectional view of the same; and Fig. 5 is a diagram showing the circuit connections.

Referring to Figs. 1 and 5, it will be seen 60 that I have provided two electromagnetically operated switches or contactors A and B. Contactor A is for making the starting connections and contactor B for making the running connections. C represents an auto- 65 transformer or compensator which is connected in circuit between the line and the motor by the closing of the switch A. M represents the electric motor to be controlled, which I have shown as a three-phase 70 motor of the squirrel cage type. This switch A is first closed, thereby connecting the motor to the line through the starting compensator and after a predetermined interval the switch B is closed and switch A opened, 75 thereby connecting the motor directly to the line.

Referring now to Fig. 1, it will be seen that contactor A comprises an operating winding 10 having a pivoted armature 11 80 which operates a shaft 12 upon which are mounted contact fingers 13—14—15—16—17, coöperating with stationary contacts, 18, 19, 20, 21 and 22. This contactor is normally in open position but when the winding 10 is 85 energized, the shaft 12 is turned on its axis and moves the stationary contacts into engagement with the fixed contacts. The contactor B is similar to contactor A, being provided with an operating winding 23 co- 90 operating with an armature 24 which turns a shaft 25 upon which are mounted the three contact fingers 26, 27, and 28 coöperating with stationary contacts 29, 30 and 31. The two contactors A and B are mechanically 95 interlocked by an interlock bar 32 which prevents the two contactors from being closed at the same time. This is a well-known arrangement and requires no further description.

Coöperating with the contactor A is a timing device comprising an arm 33 which is secured to the shaft 12 so as to be turned when the contactor is closed. A member 34 is mounted to turn freely upon the shaft 105 and coöperates with the arm 33 through a spring 35 which forces the upper ends of the arm and member apart. Pivoted to the lower end of the member 34 is the piston rod 36 of a dash pot, having a piston 37 secured 110

to the rod and operating in a cylinder 38. The piston moves freely in the cylinder from left to right as shown in Fig. 3 but is retarded in its movement from right to left. When the contactor A closes, the spring 35 will be compressed thereby giving the lower end of the member 34 a tendency to move to the left, which movement is retarded by the dash pot. In moving in the opposite direction, however, the dash pot has no substantial retarding effect.

A switch arm 39 pivoted at 40 on the shaft 25 has its free end engaged by the member 34 as the latter moves to the left (Fig. 3) so as to bridge the two contacts 41 and 42, that is, the switch arm is moved from the position in which it is wholly in engagement with the contact 41 to the position where it bridges the contacts 41 and 42 and finally engages only the contact 42. Contact 41 is connected with the winding 10 of contactor A and contact 42 is connected with the winding 23 of contactor B, so that when the switch arm is in engagement with the contact 41, contactor A will be energized, and when it is in connection with contact 42, contactor B will be energized. The two contactors A and B are, therefore, energized at the same time, but as before pointed out they cannot both close because of the mechanical interlock. The switch arm 39 is moved in the opposite direction; viz., to the right by the arm 33, which is secured to the shaft of contactor A. As shown in Fig. 3 the arm 33 and the member 34 are shaped at their lower ends to form a slot or opening 43 into which a pin 44 on the end of the switch arm 39 fits. The switch arm is therefore moved to the left slowly after the contactor A closes and is moved to the right quickly by the arm 33 when the contactor A opens. The contacts 41 and 42 which are engaged by the switch arm 39 are mounted on a plate 45 of insulating material secured to a metallic plate 46 which in turn is secured to the shaft 25 of contactor B. When the contactor B is open the plate 45 occupies the position shown in full lines in Fig. 3 and when the contactor is closed 50 the plate is turned to the position shown in dotted lines.

The operation of the switch mechanism is, therefore as follows: When the contactor A closes the arm 33 is rotated (in a clockwise direction in Fig. 3) so as to compress the spring 35, thereby causing the member 34 to move slowly in response to the spring pressure under the retardation of the dash pot. The switch arm 39 is carried forward 60 by the member 34 until it engages contact 42 while it is still in engagement with contact 41. The windings of both switches are now energized, but because of the mechanical interlock they cannot both close. The switch A being closed, therefore, prevents

switch B from closing. When the switch arm moves forward the engagement is broken with contact 41 thereby deenergizing the winding of contactor A and permitting it to open. As soon as contactor A is deenergized, contactor B which is already energized, closes, while contactor A opens. The opening of contactor A carries the switch arm 39 back to its initial position and the closing of contactor B moves the plate 45 carrying contacts 41 and 42 back in the same direction. The result is that the switch arm and the contact are moved back together, the switch arm being in engagement with contact 42. Contactor B therefore remains closed, thereby maintaining the running connection. When contactor B opens for any reason the plate 45 will return to its initial position shown in full lines in Fig. 3.

The arrangement of circuits and mode of operation are as follows: Referring to Fig. 5, 47 indicates a manually operated, normally opened switch or push button for energizing contactor A, and 48 is a normally closed switch or push button for opening the contactors. When the push button 47 is, therefore, pressed for an instant the operating winding 10 of contactor A is energized, the circuit being as follows: from line b of the three-phase supply circuit, through the contacts 49 of the overload relays 50, to the switch arm 39, thence to contact 41, wire 51, through winding 10, switch 47, stop button 48, and thence back to main c on wire 52. This causes the contactor A to close thereby connecting the motor to the line through the autotransformer C. These connections are obvious and need not be traced. When the contactor A closes, it moves the arm 33 on its pivot and compresses the spring 35. Pressure of the spring 35 upon the member 34 moves the member slowly due to the retardation of the dash pot. The switch arm 39 therefore moves slowly until it engages the contact 42, whereupon the winding 23 of contactor B is energized, the circuit being from line b through the contacts of the overload relays to switch arm 39, contact 42, winding 23, thence through the stop button 48 and back to line c by wire 52. The windings of contactors A and B are now both energized but contactor B cannot close because of the mechanical interlock which prevents it from closing while contactor A is closed. A further movement of the switch arm 39, however, disengages it from contact 41 thereby deenergizing winding 10 of contactor A. This now permits contactor B to close and contactor A to open, contactor A, 125 of course, opening before B closes. The closing of contactor B connects the motor direct to line as will be clearly seen from the drawing and also moves the plate 46 carrying the contacts 41 and 42 to the left. Since 130

the opening of contactor A will cause the switch arm 39 to also move to the left the switch arm and the plate move together, the switch arm being in engagement with contact 42, thereby maintaining the circuit of winding 23 of contactor B. The parts will, therefore, remain in this position; namely, with the contactor B closed and A opened. Contactor B is opened either by the operation of the overload relays, by failure of voltage, or by the operation of the stop button 48. When the contactor B is opened due to any of these causes the motor, of course, is disconnected from the line and the plate 5 45 is returned to the right (Fig. 5), so that the parts will assume the position shown in Fig. 5. In order to start again the push button 47 must be pressed and the operation above described repeated. It should be noted that when the contactor A closes, the push button 47 which caused the closing of the contactor is short circuited by the contact finger 53 which operates with the contactor A. The push button 47 need be 10 20 25 30 35 40 45 50 55 60 65 70 75 80 85 90 95 100 105 110 115 120 pressed only for an instant, therefore, in order to start the operation, and unless the operation is interrupted by the operation of the stop button 48, it will continue and bring the motor up to running speed.

It will be seen, therefore, that I have provided a simple and effective device which will automatically make the starting and running connections successively upon the actuation of a push button, the operations all being positive and certain. While I have described my invention as embodied in concrete form and as operating in a specific manner in accordance with the provisions of the patent statutes, it should be understood that I do not limit my invention thereto as various modifications thereof will suggest themselves to those skilled in the art without departing from the spirit of my invention the scope of which is set forth in the annexed claims.

What I claim as new and desire to secure by Letters Patent of the United States, is:—

1. A controller for electric motors comprising two electromagnetically operated starting switch and means for energizing the same, an electromagnetically operated running switch, means set in operation by the closing of the starting switch and retarded in its action for a definite interval of time, and connections whereby the said means deenergizes the starting switch and causes this switch to open and immediately thereafter energize the running switch to cause it to close.
2. A controller for electric motors comprising two electromagnetically operated switches, one for starting and one for running, a manually operated switch for controlling the starting switch, a time element device for controlling the circuits of said electromagnetic switches and normally in a position to energize the starting switch, means for setting the time element device in operation upon the closing of the starting switch, and connections whereby the time element device deenergizes the starting switch and immediately thereafter energizes the running switch.
3. A controller for electric motors comprising two electromagnetically operated switches, one for starting and one for running, a time element device for controlling the circuits of said electromagnetic switches and means for setting the time element device in operation upon the closing of the starting switch to energize the running switch and deenergize the starting switch, said time element device being returned upon the closing of the running switch.
4. A controller for electric motors comprising two electromagnetically operated switches, one for starting and one for running, a spring actuated time element device retarded in its action for controlling the circuits of said electromagnetic switches, connections whereby said device in its movement energizes the running switch and deenergizes the starting switch and means for placing the spring under strain upon the closing of the starting switch.
5. A controller for electric motors comprising two electromagnetically operated switches, one for starting and one for running, a spring actuated time element device retarded in its action for controlling the circuits of said electromagnetic switches, connections whereby said device in its movement energizes the running switch and deenergizes the starting switch, means for placing the spring under strain upon the closing of the starting switch and means for returning the time element device upon the closing of the running switch without deenergizing the latter.
6. A controller for electric motors comprising two electromagnetically operated switches, one for starting and one for running, a spring actuated time element switch member retarded in its action and set in operation by the closing of the starting switch, and a member actuated by the running switch and contacting with the said switch member to control the circuits of said electromagnetic switches.

In witness whereof I have hereunto set my hand this 6th day of January, 1919.

PAUL H. ZIMMER.
